UNITED STATES PATENT OFFICE.

FRANK C. H. STRASBURGER, OF CHICAGO, ILLINOIS, ASSIGNOR TO THE BOTTLES SPECIAL MACHINERY COMPANY, OF CHICAGO, ILLINOIS, A CORPORATION OF ILLINOIS.

FILLING-MACHINE.

SPECIFICATION forming part of Letters Patent No. 788,681, dated May 2, 1905.

Application filed July 25, 1904. Serial No. 218,013.

To all whom it may concern:

Be it known that I, FRANK C. H. STRASBURGER, a citizen of the United States, residing at Chicago, in the county of Cook and State 5 of Illinois, have invented new and useful Improvements in Filling-Machines, of which the following is a specification.

The object of this invention is to automatically center a receptacle to be filled in proper 10 relation to the filling-tube of the machine, so that the filling-tube will be sure to enter the bottle without encountering the edge of its mouth.

For convenience in explaining the invention I have shown it in the accompanying drawings in connection with the means for raising the bottle of the kind disclosed in my application Serial No. 185,112 and with a filling-valve mechanism of the kind disclosed in 15 my application Serial No. 185,161, both filed December 14, 1903; but it will be understood that the invention can be adapted for other filling-machines in which the filling-tube enters the bottle.

20 In the drawings, Figure 1 is a sectional view showing the invention with as much of the general structure of the machine as is necessary to understand the operation of the invention. Fig. 2 is an enlarged sectional view 25 of the filling-valve and bottle-guide. Fig. 3 is an elevation of the parts shown in Fig. 2 on a smaller scale.

Referring to the drawings, 10 is a liquid tank or receptacle to which the filling-valve 30 mechanism is connected, and 11 is a bottle supported on a rest 12, which is carried by the vertically-movable stem 13. The bottle is raised to operate the valve by a cam 14, which operates a crank-lever 15, connected 35 by one or more links 16 to the stem 13.

The filling-valve mechanism comprises a body 17, which has a central bore 17', into 40 the lower end of which the filling-tube 18 is secured. Rods 19 carry the liquid-valve 20, and a head 21, slidable on the filling-tube, is 45 provided with openings 19' to receive these rods. Springs 22 on the rods normally hold the liquid-valve against its seat at the upper

end of the bore 17'. The head 21 is provided with an enlarged bore 23, which communicates by a passage 23' with a valve-chamber 24, and an air-tube 25 projects into this chamber and carries a check-valve 26, which will open to permit air to flow into the bottle, while an opening 27 in the air-tube (controlled by the set-screw 28) permits air to flow from the bottle through the tube into the tank. The upper end of the air-tube projects through the body 17 and carries a valve 29 in the housing 30 within the tank, a tube 31 being connected to the housing and extending above the level of the liquid in the tank.

The present invention consists of a guide 50 slidably arranged on the filling-tube to center the bottle automatically, so that the tube will 55 enter the bottle properly without encountering the edge of its mouth, which would be apt to result in breaking the bottle and injuring the mechanism. This guide 32 is shown in its lowest position on the filling-tube in 60 Fig. 1 and in its elevated position in Fig. 2, and it is flared or bell-shaped at its lower end 33 and provided with a socket 34 to receive the mouth of the bottle, which is adapted to engage the rubber seat 35. The upper end 65 of the guide is reduced in size or contracted to enter a socket 36 in the lower end of the head 21, and the guide is provided with a bore 37 to receive the filling-tube and also with one or more passages 39 to permit air 70 to pass from the bottle into the passage formed by the bore 23 of the head. A rubber gasket 21' may be located in the socket 36. The head is prevented from slipping off of the filling-tube at its lower end by providing a stop of suitable character, as by flaring or expanding the tube, as shown at 80 85 88.

With a centering-head of this character the operator may place the bottle rapidly on the rest without being particular to observe that 90 the mouth of the bottle is exactly alined with the filling-tube, because the bottle will on its upward movement first engage the guide, which offers sufficient resistance by reason of its weight to the bottle to cause it to move 95 into proper position to receive the filling-

tube. The inner wall of the socket 34 of the guide is smooth, and the outer edge of the mouth of the bottle will slide easily and freely thereon into position. On the continued upward movement of the bottle the guide is finally moved into the socket 36 of the head and the latter moved upward to first unseat the air-valve 29 and then unseat the liquid-valve 20. While the bottle is being lowered the guide will return to its position at the lower end of the filling-tube by gravity.

Without limiting myself to the exact construction and arrangement of parts herein shown and described, what I claim, and desire to secure by Letters Patent, is—

1. In a filling-machine, the combination of a liquid-tank, a liquid-valve in the tank, a filling-tube, a head slidable on the filling-tube and connected to said valve, a valved air connection between the tank and the head, and a slidable guide normally suspended on the fill-

ing-tube at the lower end thereof to adjust the mouth of the bottle to receive the tube, said guide being provided with an air-passage to form a communication between the air connection in the head and the bottle.

2. In a filling-machine, the combination of a liquid-tank, a liquid-valve, a filling-tube, a head slidable on the filling-tube and connected to said valve, a valved air connection between the tank and the head, and a slidable guide normally suspended on the filling-tube at its lower end and provided with an air-passage to form a communication between the air connection in the head and the bottle, said guide having its upper end contracted and said head being provided with a socket at its lower end to receive the contracted end of the guide.

FRANK C. H. STRASBURGER.
